Frank H. Richterkessing, Louisville, Ky.

Application January 11, 1954, Serial No. 28,480

Term of patent 14 years

(Cl. D15—1)

FIG. 1

FIG. 2

Figure 1 is a front perspective view of a fishing chair; Figure 2 is a top plan view thereof; and Figures 3 and 4 are front and side elevational views, respectively, of the chair.

The dominant features of my design for a fishing chair reside in the portions shown in full lines.

I claim:

The ornamental design for a fishing chair, as shown and described.
